UNITED STATES PATENT OFFICE

2,448,420

EXHAUST SPARK ARRESTER

Harvey Ellis Davidson, Tulsa, Okla., assignor to
 Bethlehem Steel Company, a corporation of
 Pennsylvania

Application May 6, 1944, Serial No. 534,507

3 Claims. (Cl. 183—82)

1

My invention relates to a device for attachment to the exhaust outlet of an internal combustion engine, and more particularly to a device for separating dangerous sparks and hot carbon particles from the exhaust gases of such an engine.

Much of the power used in oil fields, for example, is provided by internal combustion engines. The exhaust gases from these engines usually contain large and small pieces of carbon which are often incandescent. If these come into contact with inflammable materials or gases, a fire may result. Hence, it is requisite in the interest of safety to cool the gases and remove the carbon before the exhaust enters the open air, and it is desirable in general to minimize the engine exhaust noise.

One object of my invention, therefore, is to provide simple and dependable means of extracting carbon inclusions from exhaust gases.

Another object is to provide a safe device for cooling said gases.

A further object is to provide substantial means for muffling exhaust noises.

Other objects, advantages and purposes of my invention will appear hereinafter in the specification and in the appended claims, and in order to describe the invention more clearly I shall now refer to the annexed two sheets of drawings forming a part of this specification and in which like figures of reference indicate like parts.

Figure 1 is a bottom plan view of my invention; Fig. 2 is a side elevation of the invention;

Fig. 3 is a vertical section taken along the line 3—3 of Fig. 2; and

Fig. 4 is a vertical section along the line 4—4 of Fig. 2.

As shown in said drawings the device is constructed of metal sheets or plates which are shaped and welded together in understood manner, and comprises a horizontally disposed tubular casing 1, closed at the ends 2 and separated by vertical walls 3 and 4 provided with round central openings 5 and 6 into three intercommunicating compartments 7, 8 and 9. The larger middle compartment 8 is provided with a tangential vertical inlet 10 directed upward toward a constricting baffle 11. Semi-circularly about the openings 5 and 6 and extending horizontally from the casing 1 in each of the smaller end compartments 7 and 9 are the scroll- or J-shaped whirler plates 12 and 13, disposed substantially as shown to reverse the direction of gas flow. The peripheral discharge openings 14 and 15 of said end compartments 7 and 9 communicate with an external discharge chamber or exhaust box 16

2

extending lengthwise of the tubular casing 1 and provided with a horizontally disposed central outlet 17.

The bottom wall of the tubular casing 1 is provided with slot-like openings 18 19 and 20 extending lengthwise of the casing, portions of said bottom wall being bent upwardly opposed to the direction of flow in each compartment to form the lips 21, 22 and 23 of the carbon traps or troughs 24, which are equipped with pipe plugs 25, 26 and 27.

In operation the exhaust gases entering the middle compartment 8 through the inlet 10, as shown by the arrows, impinge against the constricting baffle 11, thereby increasing the velocity of the gases and directing them circumferentially into a vertical whirl which divides and exhausts into the two end compartments 7 and 9 through the openings 5 and 6 in walls 3 and 4. The heavier carbon particles follow the wall of the casing and drop into the middle trough 24 when intercepted by the lip 22. In said end compartments 7 and 9 the curved whirler plates 12 and 13 divert and reverse the circumferential flow of the gases, causing the remaining lighter particles of carbon, intercepted by lips 21 and 23, to drop in similar manner into the end troughs 24, from any of which troughs 24 the accumulated carbon may be easily removed when desired by taking out the pipe plugs 25, 26 or 27.

Passing through discharge openings 14 and 15, the cleaned, cooled and quieted gases reunite in the exhaust box 16, from which through the outlet 17 they finally emerge into the atmosphere.

Although I have hereinabove shown and described my invention in considerable detail, I do not wish to be limited to the exact and specific structure shown, but may use such substitutes, modifications or equivalents thereof as are within the scope and spirit of the invention and of the appended claims.

My invention having been thus described, what I claim as new and useful and desire to secure by Letters Patent is:

1. A spark arrester for exhaust gases, comprising a horizontal unitary cylindrical casing, a plurality of intercommunicating compartments in said casing, a tangential inlet to admit exhaust gases to one of the compartments and to impart a whirling motion to said gases therein, means for assisting the whirling gases to pass therefrom into adjoining compartments, means in said adjoining compartments for reversing the direction of the moving gases, means for col-

lecting carbon particles beneath the casing, an exhaust box for receiving the spent gases and a tangential outlet for releasing said gases.

2. A spark arrester for exhaust gases, comprising a horizontally disposed cylindrical casing, a pair of annular spaced partitions forming a middle compartment and two communicating end compartments therein, a restricted tangential orifice for admitting and circumferentially directing the gases into the middle compartment, an upturned whirler plate in each end compartment for reversing the direction of gas flow therein, and a rear exhaust box for receiving the gases from the end compartments and discharging them to atmosphere.

3. A spark arrester for exhaust gases, comprising a horizontal cylindrical casing, a large central compartment in said casing, a smaller compartment at each side of the large central compartment and communicating therewith, a vertical tangential inlet to the central compartment to admit the gases, a constricting baffle plate above said inlet to accelerate and impart a whirling motion to the gases, a J-shaped whirler plate in each end compartment adapted to reverse the direction of whirling motion therein, a longitudinal slot in the bottom of each compartment, a raised lip at each slot to intercept

and direct downward carbon particles, a longitudinal trap beneath each slot for collecting said carbon particles, a plug for cleaning each trap, a discharge opening in each end compartment, an exhaust box communicating with the discharge openings and lengthwise of the cylindrical casing wherein the gases reunite, and a horizontally disposed central outlet for releasing the gases from said exhaust box.
